PATTERN MECHANISM FOR KNITTING MACHINES

Leslie Herbert Leedham, Leicester, England, assignor to Jacquard Knitting Machine Co., Inc., Union Hill, N. J., a corporation of New York

Application January 24, 1935, Serial No. 3,236
In Great Britain February 8, 1934

4 Claims. (Cl. 66—50)

This invention consists in improvements in or relating to pattern mechanisms for use in knitting machines and is applied to a mechanism of this nature comprising a perforated pattern sheet 5 or other pattern, and a plurality of selectors arranged to respond to the markings of the pattern to control a knitting effect, for example, by selection and control of the needles. Such apparatus may be used for purposes other than that of 10 needle control as, for instance, for the control of reverse plating mechanism or wrap thread patterning devices and is not limited to any particular use for which it may be employed.

Hitherto such mechanisms have not been applicable to the finest gauge machines for several 15 reasons of which the most important are

(a) The selectors of, for example, pattern mechanisms of the type here illustrated have hitherto generally been provided with selector pins and encircling compression springs with 20 guides provided in selectors for the pins. Thus the closeness of the selectors is determined by the diameter of the pin guides or recesses in the 25 selectors together with the necessary clearance for those elements at the positions of the pins.

(b) Frequently selectors must be bent or otherwise offset at one or more points along their 30 lengths, thus requiring excess lateral space. For example, in a circular knitting machine the platens over which the pattern sections of pattern 35 mechanisms of the type here shown are guided are straight and usually arranged tangentially with respect to the needle cylinder, whereas the group of selectors controlled from any one platen

must converge at their inner ends on to a circular line parallel to the circumference of the needle cylinder. Consequently it is necessary for some or all of the selectors to be bent at one or 40 more points along their lengths. Only a very small movement, lengthwise of such selectors, is permissible for any individual selector relatively to its neighbour owing to the existence of the angles at the bends. To obtain the requisite movement hitherto the selectors have been necessarily spaced apart laterally a distance which 45 renders the mechanism unsuitable for the purpose of fine patterning by needle selection in the finer gauge machines.

According to the present invention the first 50 drawback is overcome in a mechanism of the type specified by the provision for the selectors of a feeler element composed of thin strip material. Conveniently, the feeler element is in the form of a lever (e. g. a bellcrank) pivoted intermediate 55 its ends to the selector.

In a preferred example there is a spring tending always to urge the feeler extremity in a direction towards the pattern sheet and the combination is characterized in that a slot is formed in one of the two above-mentioned elements to 5 provide an opening at one end for the entry of a pivot pin supported in the other element. The slot at its opposite end extends in a direction transverse to (e. g. substantially normal to) the resultant of the force of the spring tension acting on the feeler and the resistance to movement of the latter when it engages the pattern sheet. Conveniently the slot is formed inwardly from 10 one edge of the feeler.

The invention is also designed to overcome the 15 second drawback, i. e. it permits the use of a larger number of bent or otherwise offset selectors within a given lateral dimension. To this end alternate selectors have those portions of them at which offsetting occurs disposed at different levels. Thus the latter dimension required for a group of selectors is reduced; in the example referred to above, one selector can be moved longitudinally relatively to its neighbour without engagement between bends of neighbouring 20 selectors. So far as this feature is concerned therefore the controlling factor as to the fineness of gauge resides in the distance between a selector and that which is next but one to it instead of as hitherto between adjacent selectors. 25 As a consequence, so far as this feature alone is concerned, it would be possible to employ at least twice as many selectors in the same space as heretofore.

The two main features of the present invention, as set forth above, may be employed singly or in conjunction with one another and in order that the invention may be more clearly understood a preferred example will now be described, in which both features are applied to one and 30 the same pattern mechanism as illustrated in the accompanying drawings, in which

Figure 1 is a section in a plane containing the axis of a circular knitting machine showing those 35 portions of the latter and of the pattern mechanism sufficient for the understanding of the invention.

Figure 2, on an enlarged scale, is a plan of some 40 of the selectors illustrated in Figure 1 showing their relative arrangement,

Figure 3 to the same scale as Figure 2 illustrates 45 a detail of the feeler for a selector;

Figure 4 on a still larger scale shows a view 50 seen in plan looking from above in Figure 3 of the slot formation in the selector,

Figure 5 shows in elevation on a still larger scale the feeler alone.

Figure 6 is a fragmentary view similar to Figure 1 of a modified arrangement but illustrating only portions of the selectors and the associated pattern sheet and platen.

Figure 7 is a plan of the parts shown in Figure 6.

Figure 8 is a view similar to Figure 3 showing the position of a feeler that has not entered a perforation in the pattern sheet, and

Figure 9 is a view on an enlarged scale similar to Figure 4 showing the slotted portion only of a selector.

Like reference numerals indicate like parts in all the figures of the drawings.

In the example illustrated in Figures 1 to 5, the needle cylinder is indicated at 10 with needles 11 and associated needle jacks 112 slidable in tracks 20 therein. The cam box 12 is of usual construction and will be rotated in any known manner relatively to the needle cylinder and synchronously with the cam box there will be rotated a cam carrier 13 which has a raising cam 14 for the selectors. All such parts are of known construction and consequently require no further description herein.

Supported from the frame of the machine in brackets 15 there is a plurality of platens arranged at intervals tangentially with respect to a circle coaxial with the axis of the needle cylinder and one of these platens is indicated at 16. As usual, this platen or roller has formed in it a number of spaced longitudinal grooves some of which are indicated at 17. A perforated pattern sheet 18 passes over the platen 16 and is formed with a number of lines of perforations which register successively with the grooves 17 as they are brought step by step beneath feeler pins 19 of the selectors 20, 21. As is customary with the type of apparatus illustrated, the inner ends of the selectors, adjacent the needle cylinder, lie in substantially the same plane as the outer ends of the selectors or in substantially parallel planes. The platen 16 is racked round step by step in the usual manner in the direction of the arrow in Figure 1 by known mechanism and in synchronism with the rotation of the cam box 12 and cam 14 so that for each pass of the latter a fresh line of perforations will have been brought beneath the feeler pins 19 and the selectors whose pins have been selected will have been moved by engagement with the grooves 17 towards the needle cylinder and beneath their respective jacks 112.

Each of the feeler pins 19 is at the extremity of a feeler plate 22 composed of thin strip material, laid flatwise as it were to the side of the selector, and having an upper horn 23 to which is anchored one end of a tension spring 24, the other end of which is anchored to a hook or nose 25 formed integral with the rear end of the selector. Each feeler is received within a slot 26 formed in the body of its selector and this slot is constituted by pressing out portions 27 and 28 of the material of the selector as shown clearly in the drawings. For this purpose the material of the selector is cut by the necessary slits to provide an interposed portion or embossment 29 to afford a stop to limit the movement of the feeler plate 22 in a clockwise direction as viewed in Figure 1. A pivot pin 30 about which the feeler plate 22 can rotate is secured to the lower part of the pressed out portion 27. The feeler plate has a slot 31 cut inwardly into it from a substantially

vertical edge which faces the needle cylinder and this slot is, as shown most clearly in Figure 5, inclined downwardly from its open end. The direction of the slot will be normal to the resultant of two forces passing through the axis of the pivot 5 pin and consisting of the upward pressure on the feeler pin 19 when it is pressed on to the surface of the pattern sheet as shown in Figure 3 and the pull of spring 24 which normally tends to press the feeler pin 19 on to the pattern sheet 10 and into and through a perforation in the latter when such a perforation is brought into register with the feeler pin.

By this construction a feeler plate 22 can readily be inserted in position by sliding its upper end 15 upwardly through the slot between the portions 27 and 28 of the selector and then passing the slot 31 on to the pivot pin 30 and the resultant of the two forces above mentioned will always tend to hold the feeler plate correctly mounted on 20 the pin. An advantage of this construction is that a damaged feeler plate can be readily replaced without first having to remove a pivot pin. Preferably the pivot pin is provided with an enlarged head 32 which will terminate in a plane 25 lying within that in which the outer surface of the pressed out portion 28 will lie. Alternatively, the feeler plate dimensions and/or the dimensions of the pressed out portions 27 and 28 could be modified so that the feeler pin is passed 30 through both portions 27 and 28 and secured therein.

As shown in Figure 2 each selector is offset by bending at 33 and 34 and in accordance with this invention the selectors are of two forms, one of 35 which alternates with the other in each group of selectors associated with a platen. One of the selectors throughout the length of it which embraces the two bent portions 33 and 34 extends at a level of the selector 20 shown in Figure 1, 40 whereas the adjacent selector will have that portion raised to the height of selector 21. As the selectors 20 and 21 alternate with one another the endwise movement permissible at the offset portions will be twice that which would have 45 been permissible had all the selectors been arranged at the same height throughout their lengths. The raised selector 21 terminates in a head portion 35 which at its extremity 36 will register with the similar extremity of the adjacent selector. Both these extremities are formed with slots 37 with which to engage the active edge of cam 14. The latter entering the slot, therefore, prevents any retraction of the selector until it has passed from engagement with the 50 cam. In chain lines in Figure 1 one selector such as 20 is shown in an active position to engage beneath and raise a needle jack 112 together with its associated needle 11 and to do this its associated feeler pin 19 will have been engaged in a 55 groove 17 and will have been moved forwardly by a partial rotation of the platen 16. On the other hand the neighbouring selector 21 is shown in chain lines as not having been thus selected and moved with a consequence that although it is 60 raised by the cam 14 it has not passed beneath a jack 112 and consequently it will not raise a needle. The operation of the jacquard mechanism in this respect, however, is well understood and of itself constitutes no part of the present 65 invention.

In the construction illustrated in Figures 6 to 9 the formation of the selectors so far as their lengths including the bent portions are concerned is the same as that of the previous example. In 75

the construction according to Figures 6 to 9, however, instead of forming a slot for reception of the feeler plate by pressing out portions of the material of the selector itself, a cover plate 38 of thin spring steel is now spot-welded or otherwise attached to the body of the selector to afford the necessary slot for reception of the feeler plate 122. The pivot pin 130 is now secured at its two ends between the cover plate and the body of the selector and is subject to the disadvantage, namely, that when it is required to replace a feeler plate 122 it will be first necessary to remove the pivot pin 130 and thereafter to insert the new feeler plate and a new pivot pin. An abutment 129 to limit clockwise movement of the feeler plate 122 is provided by a tongue pressed out from the material of the cover plate 38 and slot 39 is formed in the cover plate to expose a comparatively large portion of the feeler plate 122.

20 In both examples the position of the pivot 30 and 130 is such that for the small movement required by the feeler plate its feeler pin 19 and 119 is substantially normal to the surface of the pattern sheet. Both constructions result in a relatively small lateral dimension of that part of the selector which encloses the feeler plate, this dimension being considerably smaller than the corresponding dimension of similar parts of pattern mechanisms hitherto known which employ 25 the spring-pressed circular pin referred to at the commencement of this specification.

It is obvious that in the drawings only a few of the selectors have been illustrated in association with the pattern roller but it is to be understood that any desired number may be employed and any preferred number of groups of platens and their associated parts may be employed spaced in any preferred manner around the axis of the knitting machine.

40 It will be appreciated that instead of forming the slot such as 31 in the feeler plate itself the slot could have been formed in a wall such as 27, 28, or 38 or in two opposed walls and the pin itself could have been secured to the feeler plate 45 to enter such a slot or such opposed slots.

It is also within the invention to form those portions of the selectors in which offsetting occurs at more than two different heights. For instance, another series of selectors could have the 50 portions mentioned disposed below the level of the selectors such as 20 in which case three different kinds of selectors would be employed.

In general, my invention is not limited to the constructions herein illustrated and described, except as appears hereafter in the claims.

I claim:

1. In a pattern mechanism, a pattern, a selec-

tor extending therefrom to transmit the calls thereof, one edge of said selector being in juxtaposition to the pattern, a feeler lever composed of thin strip material located flatwise to the selector, said lever being pivoted to the selector intermediate the ends of the lever and with one of said ends projecting beyond said edge of the selector to engage the pattern and the other end projecting toward the opposite edge of the selector, and a spring to urge the first mentioned end of 10 the feeler lever toward the pattern, one end of the spring being connected to the selector and the other end of the spring being connected to the second mentioned end of the feeler lever.

2. In pattern mechanism, a pattern, a selector, 15 a feeler lever composed of strip material pivoted intermediate its ends to the selector flatwise thereto, one arm of the lever being adapted to engage said pattern as a feeler, and a spring anchored to said selector and engaging said lever 20 to urge the said arm of the lever toward the pattern, said feeler lever and selector being provided one with a pivot pin and the other with a slot receiving the pivot pin, the slot extending in a direction substantially transverse to the resultant 25 of the force of the spring acting on the feeler and the resistance to movement of the first mentioned lever arm when the latter engages said pattern.

3. In a circular knitting machine, the combination of a pattern, a plurality of elements of the 30 machine to be controlled by said pattern, and a plurality of selectors subject to the call of said pattern and to control the action of said elements, said selectors being movable substantially longitudinally of each other substantially individually 35 and at least some of said selectors having offset portions, characterized by the fact that adjacent selectors having offsets have portions adjacent their offsets disposed at different levels.

4. In a circular knitting machine, the combination of a pattern, a plurality of elements of the 40 machine to be controlled by said pattern, and a plurality of selectors subject to the call of said pattern and to control the action of said elements, the ends of said selectors nearer said elements being arranged substantially in a group and the opposite ends of said selectors being arranged substantially in a group that is substantially parallel to the first mentioned group, and said selectors being movable substantially individually 45 substantially longitudinally of themselves and at least some of said selectors being bent at two points to converge their inner ends toward the axis of the machine, characterized by the fact that adjacent bent selectors have their portions 50 between bends disposed at different levels.

LESLIE HERBERT LEEDHAM.
